UNITED STATES PATENT OFFICE.

ELMER SHOUP, OF WINESBURG, OHIO, ASSIGNOR OF ONE-THIRD TO ROLANDUS O. McFARREN, OF MASSILLON, OHIO, AND ONE-THIRD TO JOHN E. ARNOLD, OF MOUNT HOPE, OHIO.

DESIGN FOR A REFLECTOR FOR MOVING-PICTURE-MACHINE LIGHT.

• 50,142.

Specification for Design.

Patented Jan. 2, 1917.

Application filed September 13, 1916. Serial No. 119,988. Term of patent 3½ years.

To all whom it may concern:

Be it known that I, ELMER SHOUP, a citizen of the United States, residing at Winesburg, in the county of Holmes and State of Ohio, have invented a new, original, and ornamental Design for a Reflector for Moving-Picture-Machine Light, of which the following is a specification, reference being had to the accompanying drawing, forming part thereof.

In the drawings the figure is a perspective view.

I claim:

The ornamental design for a reflector for moving picture machine light, substantially as shown.

ELMER SHOUP.

Witnesses:

J. H. BISHOP,
SYLVIA BOROW.
